UNITED STATES PATENT OFFICE

94,327

DESIGN FOR A SERVICE BAR BACK COUNTER

Clarence W. Brown, Chicago, and Herbert Tyson,
Oak Park, Ill., assignors to The Brunswick-
Balke-Collender Company, Chicago, Ill., a corporation of Delaware

Application October 6, 1934, Serial No. 53,508

Term of patent 3½ years

To all whom it may concern:

Be it known that we, Clarence W. Brown and Herbert Tyson, both citizens of the United States, residing, respectively, at Chicago, in the county of Cook, in the State of Illinois, and at Oak Park, in said county of Cook, State of Illinois, have jointly invented a new, original, and ornamental Design for a Service Bar Back Counter, of which the following is a specification, reference being had to the accompanying drawing, forming part thereof.

In the drawing—

The figure is a perspective view of a service bar back counter showing our new design.

We claim:

The ornamental design for a service bar back counter, as shown.

CLARENCE W. BROWN.
HERBERT TYSON.
